UNITED STATES PATENT OFFICE.

WILLIAM C. BRUMDER, OF MILWAUKEE, WISCONSIN.

VOTING-MACHINE.

1,149,113.

Specification of Letters Patent. Patented Aug. 3, 1915.

Application filed May 28, 1914. Serial No. 841,458.

To all whom it may concern:

Be it known that I, WILLIAM C. BRUMDER, a citizen of the United States, residing at Milwaukee, in the county of Milwaukee and 5 State of Wisconsin, have invented certain new and useful Improvements in Voting-Machines, of which the following is a full, clear, concise, and exact description, reference being had to the accompanying drawings, forming a part of this specification.

My invention relates to voting machines and has for its object the provision of an improved voting machine system whereby a single counting mechanism may be employed, one for each candidate, actuated however by a plurality of setting or controlling mechanisms so that more than one voter may vote at the same time, thus to facilitate voting and avoid the necessity of 15 hurrying the voters. It is usually customary to have but one voting machine in a booth and under these conditions the voters must await their turn in order to operate the machine.

With my improved voting machine a plurality of voters may set the device at the same time, means being provided so that when the final act of registration is done by either controlling device, that this entire 20 registration from any other device may be held in abeyance.

As will be readily apparent my invention is applicable to both mechanical or electrical operated voting machines, but for the sake 35 of illustration I have shown my improved machine herein as being operated and controlled electrically. In this form I prefer to have a plurality of key boards or controlling mechanisms arranged in parallel or multiple 40 relation which are adapted to act upon one set of counting mechanisms, means being provided to prevent the actual simultaneous attempt at registration of two controlling mechanisms.

I will explain this form which my invention may take more particularly by referring to the accompanying drawing illustrating diagrammatically a voting machine equipped in accordance with my invention.

I show my invention herein as arranged to 50 accommodate two voters, but it will of course be understood that more devices can be readily added in multiple if desired in the manner shown for these two devices. I have 55 also shown each device as permitting the selection of but one of two candidates, it

being readily understood that the device can accommodate more series of two candidates, in which case there will also be additional counting mechanism, there naturally being 60 one counting mechanism for each candidate. As stated, I show but two counters 1 and 2, there being but two candidates to be voted for. There are two sets of controlling mechanisms A and B each controlling mechanism 65 being complete for one voter and each having complete apparatus to control registrations to be made upon the counters 1 and 2. Each controlling mechanism A and B is for the use of a voter. In the operation of the 70 controlling device A, for instance, I provide two keys 3 and 4, one corresponding to each candidate, each controlling key having an associated lamp, respectively the lamps 5 and 6. There is also provided for 75 each key a relay, respectively the relays 7 and 8. These relays serve to place the circuits leading to the counters 1 and 2 in condition ready for registration so that this registration may be effected by the movement of a turnstile 9, for instance, as the voter is leaving the booth within which is placed the mechanism A.

Assuming now that the voter wishes to vote for the candidate represented by the 85 key 3, a depression of this key closes a circuit which extends from the negative terminal of the battery 22 by way of conductor 10, switch arm 11, normal contact 12, conductor 13, resistance 14, key 3, contact 15, 90 conductor 16, winding of the relay 7, conductor 18, switch arm 19, normal contact 20, conductor 21, to the positive terminal of the battery 22. It will thus be seen that current is supplied to the relay 7 which 95 draws up its armatures 23 and 24 respectively, thereby completing a locking circuit from this relay which extends from the positive terminal of the battery by the same path as before, then by way of the armature 24, conductor 25, conductor 13, contacts 12 and 11 to the negative terminal of the battery. The relay 7 thus remains locked up. At the same time circuit is completed through the lamp 5, from the positive terminal of 100 the battery, by way of conductor 26, conductors 16 and 25, to the negative terminal of the battery. The actuation of the relay 7 completes a circuit which extends from the turnstile by way of the conductor 27, 110 through the counter actuating magnet 28, conductor 29, armature 23, to the positive

terminal of the battery, through the battery, and by way of conductor 10 to the switching spring 11. Thus it will be seen that the circuit leading to the counter 1 is complete and this counter will be actuated the moment the 5 turnstile is operated to close circuit through this turnstile or gate 9 with the spring 11.

Now in order to prevent successive actuation by one voter of the keys 3 and 4 so that 10 the voter sets the circuit to both counters, I provide a step-by-step element 30, which through the agency of its arm 31 is adapted successively to engage contact points 32, 33, etc. Actuating the key 3 completes a circuit 15 through the magnet 34 which can be traced from the positive terminal of the battery, through said magnet, conductor 35, relay 36, contact 37, key 3, to the negative terminal of the battery 22. Thus the actuation 20 of the key 3 causes a movement of the armature 38, thereby to operate the step-by-step element one step so that it engages contact 32. Now should the key 4 be depressed before a restoration of the entire control 25 mechanism, then the device 30 will be stepped around to the next contact post, respectively the contact post 33, and thereupon a circuit is established from the positive terminal of the battery, through the release 30 magnet 39, conductor 40, arm 31, conductor 41, to the negative terminal of the battery. The release magnet 39 thus actuates its 35 armature 42, whereupon to release the holding pawl 43, and the step up pawl 44 from the teeth of the step-by-step element 30, to thereby permit retraction of this step-by-step element through the agency of the spring 45. The actuation of the magnet 39 at the same time breaks the contacts between 40 the elements 19 and 20, thereby breaking the locking circuit to whatever relays 7 or 8 have been locked in position so that the entire device is restored to normal without registration.

45 Now to guard against the contingency of having two keys 3 and 4 operate at the same time to avoid the regulating influence of the step-by-step device 30, I provide the relay 36. This relay 36 is marginal and is not actuated if but one key 3 is depressed because the resistance 14 does not permit enough current to pass through this relay 36 to actuate its armature 46. When however two keys 3 and 4 are depressed simultaneously, two circuits in parallel including respectively the resistances 14 and 47 are included with the circuit leading to the relay 36 and thereupon it attracts its armature so as to close a circuit which can be traced 55 from negative battery by way of conductors 10 and 13, through the armature 46, release magnet 39, to the positive battery, thus actuating the release magnet 39 and breaking the circuit to the relays 7 and 8.

60 65 From this it will be apparent that but one

of two conductors can be selected at the same time by either of the control devices A or B. It is of course assumed that the candidates corresponding to the keys 3 and 4 belong to different parties, and there may 70 of course be additional pairs, in which case there would be duplicate mechanism similar to that illustrated herein, which however is omitted for the sake of clearness. Similarly of course there may be three or 75 four parties instead of two which would merely cause duplication of the keys and relays, but would leave the rest of the mechanism substantially the same.

Now the mechanism associated with the 80 control station B is exactly the same as that associated with the control station A and the relays 7 and 8 of the mechanism B control the counters 1 and 2 just the same as the relays 7 and 8 of the mechanism A. 85 Thus each control mechanism can actuate the counters. Now it will be readily apparent that the registrations however should not be simultaneous, and one of the many forms of mechanism which can be employed 90 to perform this result is illustrated herein as consisting of means to control the turnstiles or gates 9 and 48 leading respectively to the booths containing the devices A and B. Of course it is only at the instant that 95 one voter leaves the booth that registration from other devices is prevented so that the saving of time in having a plurality of voters set the control mechanisms is great, even though simultaneous registration is 100 prevented. To this end the gates 9 and 48 are each controlled by arms 49 pivoted at 105 50 and controlled by magnets 51. Each turnstile also controls a switch element 52 and the connection with its contact 53. Now whenever a turnstile 9 for instance is operated into the dotted position, to cause a registration, circuit is closed between the elements 52 and 53, thereby energizing all 110 of the magnets 51 from the battery 54 and actuating the arms 49. The arm 49 of the element 9 will not be moved as the gate 9 is in its path, but the arm 49 of the gate 48 will be moved into its alternative position, thus preventing movement of the gate 48 until the gate 9 is again restored to normal 115 to open the circuit between the elements 52 and 53.

From what has been thus explained it is 120 thought my invention will be entirely clear, namely that mechanism is provided whereby a single system of counting mechanisms may be used by a multiplicity of voters, means being provided to prevent simultaneous registration from two or more controlling 125 mechanisms. It will of course also be clear that the broad nature of my invention is readily susceptible of many modifications, but

Having however thus described one form 130

which my invention may take, what I claim as new and desire to secure by Letters Patent is:

1. A voting machine having a plurality of counters one for each candidate, a plurality of counter controlling devices, each said device having means to control each of said counters aforesaid, and electric means for preventing attempted simultaneous actuation of said counters by said devices.

2. A voting machine having a plurality of counters one for each candidate, a plurality of counter controlling devices, each said device including a complete key board for said candidates and having means to control each of said counters aforesaid, and electric means for preventing attempted simultaneous actuation of said counters by said devices.

3. A voting machine having a plurality of counters one for each candidate, a plurality of counter controlling devices, each said device having electromagnetic means to control each of said counters aforesaid, and means for preventing attempted simultaneous actuation of said counters by said devices.

4. A voting machine having a plurality of counters one for each candidate, a plurality of counter controlling devices, each said device including a complete key board for said candidates and having electromagnetic means to control each of said counters aforesaid, and means for preventing attempted simultaneous actuation of said counters by said devices.

5. A voting machine having a plurality of counters one for each candidate, a plurality of counter controlling devices, each said device having means to control each said counters aforesaid, switching means associated with each device interposed between said devices and said counters to control the simultaneous actuation of selected counters by the control means of each device, and means for preventing attempted simultaneous actuation of said counters by said devices.

6. A voting machine having a plurality of counters one for each candidate, a plurality of counter controlling devices, each said device including a complete key board for said candidates and having means to control each of said counters aforesaid, switching means associated with each device interposed between said devices and said counters to control the simultaneous actuation of selected counters by the control means of each device, and means for preventing attempted simultaneous actuation of said counters by said devices.

7. A voting machine having a plurality of counters one for each candidate, a plurality of counter controlling devices, each said device having electromagnetic means to control each of said counters aforesaid, switch-

ing means associated with each device interposed between said devices and said counters to control the simultaneous actuation of selected counters by the control means of each device, and means for preventing attempted simultaneous actuation of said counters by said devices.

8. A voting machine having a plurality of counters one for each candidate, a plurality of counter controlling devices, each said device including a complete key board for said candidates and having electromagnetic means to control each of said counters aforesaid, switching means associated with each device interposed between said devices and said counters to control the simultaneous actuation of selected counters by the control means of each device, and means for preventing attempted simultaneous actuation of said counters by said devices.

9. A voting machine having a plurality of counters one for each candidate, a plurality of counter controlling devices, each said device having means to control each of said counters aforesaid, gate controlled means associated with each device interposed between said devices and said counters to control the simultaneous actuation of selected counters by the control means of each device, and means for preventing attempted simultaneous actuation of said counters by said devices, said last aforesaid means including gate controlled mechanism.

10. A voting machine having a plurality of counters one for each candidate, a plurality of counter controlling devices, each said device including a complete key board for said candidates and having means to control each of said counters aforesaid, gate controlled means associated with each device interposed between said devices and said counters to control the simultaneous actuation of selected counters by the control means of each device, and means for preventing attempted simultaneous actuation of said counters by said devices, said last aforesaid means including gate controlled mechanism.

11. A voting machine having a plurality of counters one for each candidate, a plurality of counter controlling devices, each said device having electromagnetic means to control each of said counters aforesaid, gate controlled means associated with each device interposed between said device and said counters to control the simultaneous actuation of selected counters by the control means of each device, and means for preventing attempted simultaneous actuation of said counters by said devices, said last aforesaid means including gate controlled mechanism.

12. A voting machine having a plurality of counters one for each candidate, a plurality of counter controlling devices, each

said device including a complete key board for said candidates and having electromagnetic means to control each of said counters aforesaid, gate controlled means associated with each device interposed between said devices and said counters to control the simultaneous actuation of selected counters by the control means of each device, and means for preventing attempted simultaneous actuation of said counters by said devices, said last aforesaid means including gate controlled mechanism.

13. A voting machine having a plurality of counters one for each candidate, and a plurality of counter controlling devices, each said device having electromagnetic means to control each of said counters aforesaid.

14. A voting machine having a plurality of counters one for each candidate, a plurality of counter controlling devices, each said device having electromagnetic means to control each of said counters aforesaid, and electrically controlled interlocking means for preventing attempted simultaneous actuation of said counters by said devices.

15. A voting machine having a plurality of counters one for each candidate, a plurality of counter controlling devices, each said device including a complete key board for said candidates and having electromagnetic means to control each of said counters aforesaid, and interlocking means for preventing attempted simultaneous actuation of said counters by said devices.

16. A voting machine having a plurality of counters one for each candidate, a plurality of counter controlling devices, each said device having electromagnetic means to control each of said counters aforesaid.

control each of said counters aforesaid, and interlocking means for preventing attempted simultaneous actuation of said counters by said devices. 40

17. A voting machine having a plurality of counters one for each candidate, a plurality of counter controlling devices continuously in coöperative relation with their respective counters, each said device including a complete key board for said candidates and having electromagnetic means to control each of said counters aforesaid, and means for preventing attempted simultaneous actuation of said counters by said devices. 45 50

18. A voting machine having a plurality of counters one for each candidate, a plurality of counter controlling devices continuously in coöperative relation with their respective counters, each said device having electromagnetic means to control each of said counters aforesaid, and means for preventing attempted simultaneous actuation of said counters by said devices. 55 60

19. A voting machine having a plurality of counters one for each candidate, and a plurality of counter controlling devices continuously in coöperative relation with their respective counters, each said device having electromagnetic means to control each of said counters aforesaid. 65

In witness whereof, I hereunto subscribe my name this 22nd day of May, A. D., 1914. 70

WILLIAM C. BRUMDER.
